LAP JOINT FOR ROOFING AND THE LIKE

Edward S. Lawrence and George G. McGlaughlin,
Mount Lebanon, Pa.

Application September 13, 1937, Serial No. 163,683

1 Claim. (Cl. 108—18)

This invention relates to metal sheet roofing and the like, and particularly to an improved lap-joint for such sheets.

Heretofore, commercial roofing of the lap-seam type usually employed lapping edges having a sharp inverted V-shaped, longitudinally extending, crimped edge for joining the adjacent sheets together. While such roofing has been commercially successful it does have some bad features, in that it provides a channeled surface which retains moisture and tends to hasten corrosion at the joint and, further, such a construction often develops leaks around the nails that are driven down through the sharp-edged crown or vertex of both the lapping and lapped edges to hold the joining edges together and the sheets in place. Also, such nailing often, in penetrating the metal of the crown of the ridges, resulted in forming deep depressions in the metal or caused excessive downward drawing of the metal around the nail, sometimes entirely deforming the joint at that point and allowing leakage of the joint, and, also, providing an excellent well or retainer for water or moisture, thereby tending to hasten corrosion thereabout, in time allowing the nail head to pull through the sheets.

Furthermore, when nails are driven into such a sharp crown or vertex, as that of a V-shaped crimp, they are difficult to center and often, after entering the lapping edge, they are urged down the inclined side of the lapped-edge between the sheets, thus failing to enter the crown of the edge and the material to which they are to be fastened which results in the sheets not being fastened at that point. Such a condition also tends to force the joining edges apart allowing leakage along the joint.

In the present invention, these difficulties have been overcome by providing a lap-joint having substantially a wide upwardly arcuated crown portion which will not retain moisture but rather from which moisture and water will tend to escape.

It is an object of this invention to provide roofing having a lap-joint which is inexpensive to manufacture and easy to assemble, assuring a tight joint which is not subject to undue corrosion, and, at the same time, possessing all the other qualities required of a good roofing.

Various other objects and advantages of our invention will more fully appear during the course of the following specification and will be more particularly pointed out in the appended claim.

In the accompanying drawing we have shown,

for the purpose of illustration, one embodiment which our invention may assume in practice.

In the drawing:

Figure 1 is a plan of a section of a roofing sheet, showing the improved lap-joint of our invention;

Figure 2 is a sectional view taken on the line II—II of Figure 1; and

Figure 3 is an enlarged cross-section, similar to Figure 2 showing the improved lap-joint.

Metal roofing and the like is made in sheets of a size that can be easily and conveniently handled. Each of the sheets is usually the same, having side edge portions which are adapted to be joined in overlapped relationship; and each usually has a formed lapped-edge along one side and a formed lapping edge along the other side which is adapted to cooperate with the lapping and lapped edges, respectively, of the adjacent sheets to join them, as is well understood by those skilled in the art.

It is to these lapped and lapping edges that this invention relates. There is shown in the drawing metal roofing sheets 5 and 6, having a lapped-edge 7 on one side of the sheet and a lapping edge 8 on the opposite side.

The lapped-edge consists of a longitudinally upwardly extending main ridge 9 of substantially an inverted U-shaped cross-section having downwardly diverging opposed side-walls 10 connected by an upwardly arcuated crown portion 11, which are yieldable relative to each other. These side-walls terminate in horizontal flat portions 12 which are disposed substantially in the plane of the body of the sheet. The horizontal flat portion, toward the center of the sheet, terminates in a second smaller longitudinally extending ridge 13 of substantially an inverted V-shaped cross-section having side-walls 14 and 15, with the inner side-wall 15 of the V-shaped ridge terminating in the plane and body of the sheet. The other horizontal flat portion terminates in a longitudinally upwardly extending angular flanged edge 16, preferably at an angle of about 45 degrees.

The lapping edge consists of a longitudinally upwardly extending ridge 17 of substantially an inverted U-shaped cross-section which is substantially larger than the main U-shaped ridge 9 of the lapped-edge and which is adapted to receive and house the same, and has downwardly diverging opposed side-walls 18 and 19, appreciably shorter than the side-walls 10, connected by an upwardly arcuated crown portion 20 conforming to the crown portion 11 of the lapped-

- edge. These side-walls terminate in horizontally disposed flat portions 21 which are parallel to and spaced from the horizontal flat portions 12 of the lapped-edge. The horizontal flat portion toward 5 the center of the sheet terminates in a downwardly angularly extending portion 22, which contacts the end of the flanged portion 16 of the lapped-edge at 23 on its underside, finally terminating in the plane and body of the sheet.
- 10 The other horizontal flat portion 21 of the lapping edge terminates in a downwardly angularly extending flanged portion 24, contacting the outside surface of the inner side 15 of the V-shaped ridge 13 of the lapped-edge, which finally terminates in a turned-out edge 25 substantially in 15 the plane of the sheet.

There is provided on the outer and topmost central portion of the arcuated crown 26 of the U-shaped ridge of the lapping edge 8, predetermined spaced indentations 28 which tend to 20 guide and center the point of nails through the crown portion of the ridges and the metal of the sheet.

It will be noted that the U-shaped ridge of the 25 lapping edge is substantially larger than the U-shaped ridge of the lapped-edge which allows the yieldable side-walls 10 of lapped-edge, when nailed or fastened, to spring apart or yield until they contact the lower terminating edges of the 30 side-walls 18 and 19 of the U-shaped ridge of the lapping edge. Such a construction allows for excess nailing and eliminates buckling of the edges, as often happens to such edges which are not constructed according to this invention.

35 While we have, in this application, specifically shown and described an embodiment of our invention, it will be understood that this is merely for the purpose of illustration and description and that various other forms may be devised 40 within the scope of our invention, as defined in the appended claim.

We claim:

A lap-joint for roofing and the like comprising

sheets adapted to overlap along their meeting edges, each of said sheets having a lapped-edge consisting of a longitudinally upwardly extending main ridge of substantially an inverted U-shaped cross-section, said ridge having diverging opposed 5 side-walls connected by an upwardly arcuated crown portion, each of said side-walls terminating in horizontal flat portions disposed substantially in the plane of said sheet, the horizontal flat portion toward the center of the sheet terminating in 10 a second smaller longitudinally extending ridge of substantially an inverted V-shaped cross-section, the inner side of which terminates in the plane and body of said sheet and the other horizontal flat portion terminating in a longitudinally up- 15 wardly extending angular flanged edge, and a lapping edge consisting of a longitudinally upwardly extending overlapping ridge of substantially an inverted U-shaped cross-section for receiving the top of the U-shaped ridge of the 20 lapped-edge, said ridge of the lapping edge having diverging opposed side-walls connected by an upwardly arcuated crown portion conforming to the arcuated crown of the U-shaped ridge of the 25 lapped-edge, said side-walls being spaced farther apart than the side-walls of the U-shaped ridge of the lapped-edge and each terminating in horizontally disposed flat portions spaced from and substantially parallel to the horizontal flat portions of the lapped-edge, one of the horizontal flat 30 portions of the lapping edge terminating in a downwardly angularly extending portion contacting the extreme edge of the angular flange of the lapped-edge on its underside and terminating in the plane and body of the sheet, and the other horizontal flat portion terminating in a downwardly angularly extending flanged portion contacting the said inner side of the inverted 35 V-shaped ridge of the lapped member and finally terminating in a turned edge substantially in the plane of the sheet.

EDWARD S. LAWRENCE.
GEORGE G. McGLAUGHLIN.
